UNITED STATES PATENT OFFICE.

ARTHUR J. MOXHAM, OF NEW YORK, N. Y.

MACHINE FOR TREATING EXPLOSIVE MATERIAL.

1,299,500.

Specification of Letters Patent.

Patented Apr. 8, 1919.

Application filed December 17, 1917. Serial No. 207,435.

To all whom it may concern:

Be it known that I, ARTHUR J. MOXHAM, a subject of the King of Great Britain, residing at New York city, county of New York, and State of New York, have invented a new and useful Improvement in Machines for Treating Explosive Material, of which the following is a full, clear, and exact description, reference being had to the accompanying drawings, which form a part of this specification.

In the manufacture of explosives, a frequent cause of accidental explosions is the sparking that sometimes occurs in and around moving machinery due to friction between the parts. The object of my invention is to prevent sparking in such moving machinery and thereby eliminate one important cause of accidental explosions and thus render the manufacture of explosives more nearly absolutely safe.

The result sought is accomplished by immersing all parts of the machinery in which sparking may be apprehended, such as bearings, gearing, or other intermeshing, rolling or sliding parts, in water or other suitable non-spark-propagating liquid and by constructing the wearing parts of material which will be self-lubricating and will not be injuriously affected by continuous immersion in the liquid.

Examples of constructions embodying my invention are shown in the accompanying drawings, in which—

Figure 1 is a plan view of a shell carrying carriage on its track in a trough.

Fig. 2 is a cross section through same, and

Fig. 3 is a longitudinal section.

Fig. 4 is a side elevation of a mixer.

Fig. 5 is a more or less diagrammatic end view of same.

Fig. 6 is a plan view of one of the gear pits.

The carriage *a* of Figs. 1, 2 and 3 is mounted on wheels *b*, which travel on rails *c* embedded in a concrete or other waterproof trough *d*, the side walls of which extend up to above the tops of the wheels *b*. A socketed projection *e* depending from the bottom of the car is engaged by a plug *f* on the chain *g*, which travels longitudinally through the trough *d*. The chain *g* is carried by one or more wheels *h* which travel on an iron rail *i* embedded in the bottom of the trough.

All bearings and other parts needing lubrication are constructed of a self-lubricating material which will not be affected by immersion in the water with which the trough is filled to about the level *x*—*x*. I prefer to make these parts of brass containing pressed plumbago, the lubrication of which is not effected by the water.

It will be observed that all intermeshing or coacting parts the relative movement of which might, under ordinary conditions, produce friction from which a spark might be developed, are under the water level and it is therefore impossible to develop a spark.

In Figs. 4, 5 and 6 is represented a mixer such as is used in the manufacture of ammonium nitrate. The stationary drum *m* is mounted upon a rotating shaft *n*, which carries, within the drum, two spirals *o* and *p*, one spiral *o* being outside the other *p* and reversely arranged so that the material being mixed is fed in one direction by one spiral and in the other direction by the other spiral. The shaft *n* is carried at its opposite ends by solid bearing wheels *r*, each of which rests upon a pair of smaller supporting wheels *s*. A relatively small driving gear wheel *t* at each end of the mixer is in driving engagement with a large gear wheel *u* on the shaft *n*. Rotation of gear *t* rotates the gear *u* and shaft *n* and operates the spirals as described. After the material has been properly mixed it can be taken out through an opening in the lower part of the drum, which is closed at other times by a slide *w*. The drum may be charged through a similar opening in the upper part of the drum having a similar slide *y*.

Wheels *s*, gears *t* and driving connections therefor are located in pits *v*. *z*—*z* represents the desirable water level for the apparatus described, all parts of which likely to produce sufficient friction to cause a spark being thus immersed in water.

The specific construction shown and described illustrate known machines modified to adapt them to be so far immersed in water as to avoid the possibility of sparks produced by the friction of coacting parts. The invention is not only adapted, without involving any complication of mechanism, to those machines in which such parts are exposed and in dangerous proximity to the explosive material undergoing treatment, but it is also adapted to those machines in which

the actuating mechanism is driven from the top, such machines readily lending themselves, usually with some advantage in the way of simplicity of construction, to such alteration as would be involved in locating such mechanism below the level of the explosive materials, whereby, as in the examples herein given, it is practicable to immerse such mechanism in water.

10 It will be understood that in specifying immersion in a body of liquid I do not mean to be confined to anything in the nature of a pool of water confined within a trough or the like, it being evident that a current of 15 water flowing horizontally, or dropping vertically, or continuously sprayed, or otherwise applied, so as to maintain friction-producing parts so covered with water as to prevent the formation or propagation of sparks, 20 accomplishes the same results in substantially the same way and is an equivalent of the specific and preferred embodiment of the invention herein more particularly described.

25 Having now fully described my invention, what I claim and desire to protect by Letters Patent is:

1. In machines for treating explosive material, the combination with the means for directly operating upon such material, of actuating mechanism for said means, and a body of liquid in which are immersed parts of said actuating mechanism whose frictional action would otherwise tend to produce sparks.

2. In machines for treating explosive material, the combination with the actuating mechanism, of a spark-extinguishing liquid in which are immersed parts of said actuating mechanism whose frictional action would otherwise tend to produce sparks, said

parts being composed of self-lubricating material.

3. In machines for treating explosive material, the combination with actuating mechanism comprising parts which if exposed would tend by their frictional action to produce dangerous sparks, of a body of spark-extinguishing liquid immersing said parts whose level is below that part of the mechanism which is in direct contact with the explosive material.

4. In a machine for treating explosive material, the combination with actuating mechanism comprising parts whose frictional action would, if exposed, tend to produce dangerous sparks, of a body of water in which said parts are immersed, said parts being composed of brass containing pressed plumbago.

5. In machines for treating explosive material, the combination with the means for directly operating upon such material, of actuating mechanism for said means, and a body of liquid maintained in contact with parts of said actuating mechanism whose frictional action would produce sparks and maintained out of contact with the means for directly operating upon the material.

6. In machines for treating explosive material, the combination with the means for directly acting upon such material, of actuating mechanism for said means all the parts of which whose frictional action would produce sparks are arranged entirely below the level of said means, and a body of liquid in which said parts are completely immersed.

In testimony of which invention, I have hereunto set my hand, at New York, N. Y., on this 4th day of December, 1917.

ARTHUR J. MOXHAM.
